COMPLETION VALVE

Marvin H. Grove, 340 Hillside Ave., Piedmont, Calif.

Filed Oct. 5, 1959, Ser. No. 57,796

Term of patent 14 years

(Cl. D78—1)

FIGURE 1 is a front elevational view of a completion valve showing my new design.

FIGURE 2 is a top plan view thereof.

FIGURE 3 is a rear elevational view thereof; and

FIGURE 4 is a fragmentary side elevational view of the left side thereof.

I claim:

The ornamental design for a completion valve substantially as shown.
